Claims priority, application Germany March 7, 1953

9 Claims. (Cl. 52—7)

This invention relates to an improvement in firedamp proof explosives of increased power comprising an alkali nitrate and ammonium chloride.

As is disclosed in German patent specification 175,391 ("Process for the Production of Safety Explosives") of the year 1902, explosives which contain ammonium chloride and an equivalent proportion of potassium nitrate or sodium nitrate exhibit a high degree of safety against firedamp. In addition, the chlorine in the ammonium chloride should be completely taken up by the potassium or sodium present, so that the vapours evolved should contain no free hydrochloric acid. However, since quite different standards were imposed at that time on the safety of explosives against firedamp, the explosives then considered safe scarcely conform to the conditions of present-day permitted explosives.

A method based upon the disclosure of the aforesaid patent has recently been applied because such explosives have less tendency to harden and agglomerate in storage than the explosives hitherto employed. It has been found that the firedamp safety thus obtained does not substantially exceed the limits of that hitherto obtained.

It has now been found possible to produce firedamp proof explosives comprising a mixture of alkali nitrate and ammonium chloride capable of reacting together to form an alkali chloride and a highly sensitive explosive component, in which the grain fineness of the two salts is such that the proportion of the highly sensitive component in said explosives can be made larger than the corresponding proportions hitherto used in such explosives. The explosive power or detonation of these new explosives is consequently also greater than that of the corresponding explosives.

Almost all permitted explosives contain a highly sensitive component generally nitroglycerine and nitroglycerol, in addition to diglycol dinitrate, or dinitrochlorhydrin, or a mixture of a number of blasting oils or solid explosives, such for example as nitropentaerythritol, which to some extent represent the carrier of the detonation and must be present in such quantity that the propagation of the detonation in the explosive itself and the transmission of the detonation from one cartridge to another are ensured. In order to reduce the high explosion temperature and the high pressure of the shock wave of this explosive component to such an extent that mixtures of methane and air are not ignited, inert salts such as sodium chloride and sodium bicarbonate have hitherto generally been added. However, if, for example, a mixture of equivalent quantities of ammonium chloride and sodium nitrate is employed instead of the said salts, sodium chloride is formed by double decomposition in addition to ammonium nitrate. This sodium chloride, in contrast to sodium chloride which is added as such to the explosive, is present in a substantially more finely distributed state, and has been found to increase the firedamp safety of the explosive in which it is produced.

It is believed that the energy-supplying reaction of

2

the ammonium ion with the nitrate ion in the pair of salts takes place so slowly, in contrast to what happens in the detonation of the highly sensitive component, that this energy-supplying reaction does not substantially increase the detonation shock, but only prolongs it. This difference in the speed of reaction is believed to result from the fact that, in the highly sensitive component, the oxygen and the combustible hydrogen and carbon containing compound are present in the same molecule, while, in the pair of reactive salts, the oxygen in the sodium nitrate crystals is present separately from the combustible substance, i. e. the sal ammoniac crystals. The latter reaction is therefore partly dependent upon the grain fineness of the nitrate and of the sal ammoniac and the reaction of the salts in the detonation can consequently be controlled by their grain fineness. It has been found that, since the pair of salts must be present in a grain fineness which is particularly favourable for firedamp safety and power, the proportion of the highly sensitive component depends in turn upon this grain fineness of the salts.

It has also been found that the maximum firedamp safety is obtained with optimum explosive power if, when employing the pair of salts, ammonium chloride and sodium nitrate, a grain fineness is chosen such that at least 20% and at most 90% of said salts will pass through the German Industrial Standards sieve No. 60. The quantity of highly sensitive component must in this case be between 7 and 12%. By conforming to these conditions, it is possible to increase the lead block expansion while maintaining their permitted degree of firedamp safety.

If, for example, sodium nitrate of which 32% is finer than 0.1 mm., and ammonium chloride of which 22% is finer than 0.1 mm., are employed and a stoichiometric mixture is prepared therefrom, 7% of blasting oil is necessary in order to produce an explosive having a good detonating action, with a good firedamp safety. If the quantity of blasting oil is increased to 8% and more, the safety against firedamp is considerably decreased. If sodium nitrate and ammonium chloride are used, of which 80% is below 0.1 mm., an addition of 10.5% of blasting oil will still allow a safe transmission of the detonation, while with a grain fineness of 94% below 0.1 mm., an addition of 13.5% of blasting oil is necessary for transmission. However, it is found that, with this last increased addition of blasting oil, the optimum firedamp safety is no longer afforded.

In the said pair of salts, the ammonium chloride may be replaced by other chlorine-containing substances which are not salts but which react with the sodium nitrate present and thereby generate gas and heat. In all cases, the quantity of sodium nitrate present must be at least sufficient to combine with all the chlorine evolved during the reaction. Such chlorine-containing substances are, for example, hexachlorocyclohexane or dinitrochlorhydrin, the latter also being capable of simultaneously performing the function of the highly sensitive component.

The systems hitherto mentioned, which form sodium chloride by an internal reaction, are the most favourable with regard to the vapours evolved, since the sodium chloride which is in the form of a thick fog does not produce any irritation of the respiratory passages. Alternatively, the sodium nitrate may be entirely or partially replaced by other nitrates, particularly of metals chosen from Group Ia or IIa of Mendeleef's Periodic Table of the Elements, such as potassium or calcium.

Instead of the chlorine-containing substances, carbon-containing and hydrogen-containing salts such as ammonium oxalate or sodium acetate, which form sodium carbonate with the nitrate present, may be employed. Organic substances such as wood meal, urea and guanidine nitrate may also be employed. In all such cases,

the grain fineness of the reacting substances and the quantity of highly sensitive explosive component are so adapted to one another that the optimum firedamp safety and explosive force are obtained.

In addition to the reactive substances, inert substances may also be added, as in the case of the known permitted explosives.

The foregoing invention is now illustrated by the following examples:

Example 1

Nitroglycerine	percent	4.2
Nitroglycerol	do	2.8
Argillaceous earth	do	0.5
Sodium nitrate, 32% finer than 0.1 mm.	do	56.8
Ammonium chloride, 22% finer than 0.1 mm.	percent	35.7
Lead block expansion	cc	79
Detonation transmission with a cartridge diameter of 32 mm.	cm	15

Safety against methane-air mixture: safe with the maximum charge of 16 cartridges in the angle-shot mortar.

Example 2

Nitroglycerine	percent	6.3
Nitroglycerol	do	4.2
Argillaceous earth	do	0.5
Sodium nitrate, 80% finer than 0.1 mm.	do	54.6
Ammonium chloride, 80% finer than 0.1 mm.	percent	34.4
Lead block expansion	cc	81
Detonation transmission with a cartridge diameter of 32 mm.	cm	2

Safety against methane-air mixture: safe with the maximum charge of 16 cartridges in the angle-shot mortar.

This principle is applicable not only to the firedamp explosives of class III, but also to explosives of the other classes, as follows:

Example 3

Nitroglycerine	percent	7.5
Nitroglycerol	do	5
Argillaceous earth	do	0.5
Potassium nitrate, 80% finer than 0.1 mm.	do	51
Ammonium chloride, 80% finer than 0.1 mm.	percent	32
Wood meal	do	4
Lead block expansion	cc	148
Detonation transmission with a cartridge diameter of 32 mm.	cm	14

We claim:

1. An improved, high-power, firedamp-proof explosive composition, consisting essentially of a major proportion in the range from about 51% to about 56.8% of a mixture consisting of a finely disintegrated alkali nitrate powder having grain diameters below 0.1 mm. to the extent of at least 20% and at most 90% of said nitrate powder, and a minor proportion in the range from about 32% to about 35.7% of ammonium chloride powder in a similarly finely disintegrated state with grain diameters varying in the same range as those of said alkali nitrate, and from 7 to 12% by weight based on said explosive composition of an explosive sensitizing agent selected from the group consisting of the explosive materials nitroglycerine, nitroglycerol, diglycol dinitrate, dinitrochlorhydrin, nitropentaerythritol, and any mixture of these explosive materials.

2. An improved high-power, firedamp-proof explosive composition consisting essentially of a major proportion in the range from about 51% to about 56.8% of a salt mixture consisting of sodium nitrate powder having grain diameters below 0.1 mm. to the extent of at least 20% and at most 90% of said nitrate powder, and a minor proportion in the range from about 32% to about 35.7%

of ammonium chloride powder in a similarly finely disintegrated state having grain diameters varying in the same range as those of said nitrate powder, and from 7 to 12% by weight based on said explosive composition of an explosive sensitizing agent selected from the group consisting of the liquid explosive materials nitroglycerine, nitroglycerol, diglycol dinitrate, dinitrochlorhydrin, solid explosive materials such as nitropentaerythritol and any mixture of said liquid and solid explosive materials.

3. An improved high-power, firedamp-proof explosive composition consisting essentially of a major proportion in the range from about 51% to about 56.8% of a mixture consisting of potassium nitrate in a finely disintegrated state, having grain diameters below 0.1 mm. to the extent of at least 20% and at the most 90% thereof, and a minor proportion in the range from about 32% to about 35.7% of ammonium chloride in a similarly finely disintegrated state, with grain diameters varying in the same range as those of said nitrate, and between 7 and 12% by weight based on said explosive composition of an explosive sensitizing agent selected from the group consisting of the liquid explosive compounds nitroglycerine, nitroglycerol, diglycol dinitrate, dinitrochlorhydrin, and solid explosive compounds such as nitropentaerythritol, and any mixture of said liquid and solid explosive compounds.

4. An improved high-power, firedamp-proof explosive composition, consisting essentially of a major proportion in the range from about 51% to about 56.8% of a mixture consisting of alkali nitrate which is selected from the group consisting of sodium and potassium nitrate and mixtures thereof, and is finely disintegrated to possess grain diameters below 0.1 mm. to the extent of at least 20% and at most 90% thereof, together with a minor proportion in the range from about 32% to about 35.7% ammonium chloride in a similarly finely disintegrated state, and comprising between 7 and 12% by weight based on said explosive composition of an explosive sensitizing agent selected from the group consisting of nitroglycerine, nitroglycerol and mixtures of the latter compounds in any proportions.

5. An improved high-power, firedamp-proof explosive composition consisting essentially of about 4.2% of nitroglycerine, about 2.8% of nitroglycerol, about 56.8% of powdered sodium nitrate having grain diameters smaller than 0.1 mm. to the extent of about 32%, and 35.7% of powdered ammonium chloride having grain diameters smaller than 0.1 mm. to the extent of about 22%.

6. An improved high-power, firedamp-proof explosive composition consisting essentially of about 6.3% of nitroglycerine, about 4.2% of nitroglycerol, about 54.6% of powdered sodium nitrate having grain diameters smaller than 0.1 mm. to the extent of about 80% thereof, and about 34.4% of powdered ammonium chloride having grain diameters smaller than 0.1 mm. to the extent of about 80% thereof.

7. An improved high-power, firedamp-proof explosive composition consisting essentially of about 7.5% of nitroglycerine, about 5% of nitroglycerol, about 51% of powdered potassium nitrate having grain diameters smaller than 0.1 mm. to the extent of about 80% thereof, and about 32% of powdered ammonium chloride having grain diameters smaller than 0.1 mm. to the extent of about 80% thereof.

8. In a blasting cartridge, an improved high-power, firedamp-proof explosive composition consisting essentially of a major proportion in the range from about 51% to about 56.8% of a mixture consisting of an alkali nitrate in a finely disintegrated state with grain diameters below 0.1 mm. to the extent of at least 20% thereof and at most 90% thereof, and a minor proportion in the range from about 32% to about 35.7% ammonium chloride in a similarly finely disintegrated state, with grain diameters varying in the same range as those of

said alkali nitrate, and comprising between 7 and 12% by weight based on said explosive composition of a liquid explosive sensitizing agent selected from the group consisting of the explosive compounds nitroglycerine, nitro-glycol, diglycol dinitrate, dinitrochlorhydrin, and any mixture of said explosive compounds.

9. In a blasting cartridge, a firedamp-proof blasting explosive composition with a high explosive power, consisting essentially of a major proportion in the range from about 51% to about 56.8% of a mixture consisting of an alkali nitrate in a finely disintegrated state with grain diameters below 0.1 mm. to the extent of at least

20% and at most 90% thereof, and a minor proportion in the range from about 32% to about 35.7% ammonium chloride in a similarly finely disintegrated state with grain diameters varying in the same range as those of said alkali nitrate, and comprising between 7 and 12% by weight based on said explosive composition of a solid explosive sensitizing agent such as nitropentaerythritol.
